UNITED STATES PATENT OFFICE

121,601

DESIGN FOR A WATER BOTTLE OR SIMILAR ARTICLE

Mary Marjorie Smith, Lancaster, Pa., assignor to Armstrong Cork Company, Lancaster, Pa., a corporation of Pennsylvania

Application May 27, 1939, Serial No. 85,233

Term of patent 14 years

To all whom it may concern:

Be it known that I, Mary Marjorie Smith, a citizen of the United States, residing in Lancaster, county of Lancaster, and Commonwealth of Pennsylvania, have invented a new, original, and ornamental Design for Water Bottles or Similar Articles, of which the following is a specification, reference being had to the accompanying drawings in forming a part hereof, in which

Figure 1 is a view in side elevation, and Figure 2 is a view in front elevation of a water bottle or similar article embodying my new design.

I claim:

The ornamental design for a water bottle or similar article, substantially as shown.

MARY MARJORIE SMITH.
